UNITED STATES PATENT OFFICE.

JOHN JAMES WEAKLEY, OF GLOVERSVILLE, NEW YORK, ASSIGNOR TO
JOHN T. SHANAHAN, OF GLOVERSVILLE, NEW YORK.

TRANK FOR FINGER-TIPPED GLOVES.

No. 836,476.

Specification of Letters Patent.

Patented Nov. 20, 1906.

Application filed October 22, 1903. Serial No. 178,008.

To all whom it may concern:

Be it known that I, JOHN JAMES WEAKLEY, a citizen of the United States, residing at Gloversville, in the county of Fulton, State of New York, have invented certain new and useful Improvements in Tranks for Finger-Tipped Gloves, of which the following is a specification accompanied by drawings.

This invention relates to finger-tipped gloves.

One object of my invention is to provide a more accurately-finished glove having finger-tips.

Another object as compared with that class of finger-tipped gloves in which the tips are formed as extensions of the fingers themselves is to provide for the use of thinner pieces for the reinforcing-tips.

With these general objects in view my invention consists of a trank for finger-tipped gloves for carrying out the above objects, as will be clear from the description and drawings, and the novel features of which will be specifically pointed out in the claims.

Figure 1 is a plan view of a web of fabric suitable for forming tranks therefrom in accordance with my invention, strips of reinforcing material being also sewed on according thereto. Fig. 2 is a plan view showing tranks cut out from such a web as shown in Fig. 1. Fig. 3 is a plan view of a cut glove-blank. Fig. 4 is a perspective view of a glove after it has been made, and Fig. 5 is a section through the tip of a finger.

Referring to the drawings, *a* indicates a suitable piece of material consisting of the fabric from which the glove is to be eventually made, it being customary to cut out from this tranks which extend longitudinally of the warp of the web used, thus securing in the glove the desired transverse elasticity permitted by the weft.

The trank usually tapers from one end toward the other—that is, from the wristband end toward the finger end. The blank or piece of material *a* may be of any desirable material—such as silk, cotton, mercerized cotton, &c.—and of any thickness; but, as will appear hereinafter, the thickness of the reinforcing-tips does not under the present invention have to be the same as that of the body of the glove produced from such piece.

It was known before my invention that finger-tips could be produced by turning

back one end of a trank to form a transverse strip, cutting out the glove first and then sewing, as usual. This method possesses the disadvantage that the finger-tips have to be of the same material and thickness as the body of the glove.

According to my invention there is sewed across a piece of fabric, such as *a*, and in the direction of the weft, so as to extend transversely thereto, a flexible strip *b* of suitable material, which is advantageously thinner than the material of the glove to be eventually produced. The strip *b* is sewed to the inner side of the piece, or to that side which is to be the inside of the glove, by a line of blindstitching *c*, which secures the inner edge of the strip to that portion of the piece which is to eventually be the finger end of the trank at such a distance from the extreme edge of the piece as corresponds approximately with the width of the strip. Having now sewed to the blank the strip *b*, the tranks *d* are cut out and a number of them piled one on the other, whereupon the usual die is brought down to cut out glove-blanks, such as shown in Fig. 3. Each cut glove-blank is then made into the glove in the usual manner to form a glove, such as shown in Fig. 4, and to provide a reinforced finger, such as is shown in section in Fig. 5.

It is not necessary to go into a detailed description of how the glove is sewed up; but it may be stated in a general manner that it is customary to sew the same wrong side out and then attach the thumb, the gored insertions at the sides of the fingers being sewed in in the usual manner.

It is evident that by first sewing on a strip, such as *b*, to the eventual finger-end each cut glove, as shown in Fig. 3, will be provided with a finger-tip *e*. Each cut glove-blank is therefore provided with the usual finger-tip, such as *e*, that is formed simultaneously with the act of cutting out the glove by the dies. It is a very simple matter to connect the strips *b* with pieces *a* by lines of stitches, such as *c*, as compared with attaching each reinforcing finger-tip, such as *d*, to the fingers after they have been cut, as thereby a considerable saving of time and labor in making up a given number of gloves is had. Besides, in the whole output there will be many less defective finger-tipped gloves than where the usual way of attaching the tips separately to

the fingers is resorted to. If the strip which is to form the reinforcing part is turned over from the end of the trunk, my method would not be performed, and where this is done it is only possible to obtain finger-tips which are of exactly the same material and thickness as the trunk or the glove to be eventually produced.

Having thus described my invention, what I claim as new therein, and desire to secure by Letters Patent, is—

1. A trunk for a finger-tipped glove, the same consisting of a main portion or trunk proper, and a separate strip of reinforcing material sewed transversely across the narrower finger portion of the trunk, at the inner

edge of the strip, and at a distance from the extreme end of the trunk corresponding approximately with the width of the strip.

2. A trunk for a finger-tipped glove, consisting of a main portion or trunk proper, and a separate strip of reinforcing material secured transversely across the finger portion of the trunk along the inner edge of the strip.

In testimony whereof I have signed this specification in the presence of two subscribing witnesses.

JOHN JAMES WEAKLEY.
